O. H. FRANK,
GAS HEATER FOR SADIRONS,
APPLICATION FILED APR. 6, 1921.

1,424,460.

Patented Aug. 1, 1922.

Inventor

Otto H. Frank,

By *Walton Harrison*,
his attorney.

UNITED STATES PATENT OFFICE.

OTTO H. FRANK, OF BROOKLYN, NEW YORK.

GAS HEATER FOR SADIRONS.

1,424,460.

Specification of Letters Patent. Patented Aug. 1, 1922.

Application filed April 6, 1921. Serial No. 458,878.

To all whom it may concern:

Be it known that I, OTTO H. FRANK, a citizen of the United States, residing at Brooklyn, county of Kings, and State of New York, have invented certain new and useful Improvements in Gas Heaters for Sadirons, of which the following is a full, clear, and concise description.

My invention relates to gas heaters for sad irons, and comprehends device of this type admitting of rather general use and adapted for heating sad irons of the kind commonly used in the household as well as by tailors and other persons for pressing clothes and the like by hand. My device also admits of use for broiling and toasting, as well as for heating various articles.

More particularly stated, I seek to produce a device of the general type just mentioned, and in which I make use of a minimum number of parts, the various parts having such form as to enable them to be readily made by casting or otherwise. I further seek to give the parts such form as to render them easy to standardize, and to admit of quantity production.

In addition, I seek to give the parts such form as to enable the device to be operated with the use of comparatively little gas, and to effect a saving of time and labor upon the part of the operator.

In addition, I seek to give various parts of my device such form as to prevent the heat employed from doing damage to certain fragile parts of the device and from unduly melting the wax a portion of which is carried by the device.

My invention has other advantages, described below.

Reference is made to the accompanying drawings forming a part of this specification, and in which like reference characters indicate like parts throughout the figures.

Figure 1 is a plan view of my device, certain parts connected therewith being shown in section.

Figure 2 is a section on the line 2—2 of Figure 1, looking in the direction indicated by the arrows.

A casting 4 is made in the form shown, and comprises three pan-like members 5, 6 and 7, all integral, the pan-like member 6 being provided centrally with a hole 8, and the pan-like member 7 being similarly provided with a centrally disposed hole 9.

The pan-like member 5 is provided with

lugs 10, and the pan-like member 7 is provided with lugs 11. The lugs 10, 11 are rounded, as shown in Figure 2, and serve to support the device upon a table or the like, as indicated at 10.

A cleaning pad 12 rests upon a disk 13 of asbestos or other fireproof material in sheet form. This is for the purpose of preventing the cleaning pad 12 from scorching or burning in consequence of heat from the pan-like member 6.

The cleaning pad 12 may be of the usual or any desired construction.

At 14 is shown a cake of wax, resting upon a disk 15 of asbestos or other fireproof material, in sheet form. This disk 15 has a tendency to prevent the cake of wax from melting in consequence of heat from the pan-like member 7. It also tends to prevent the wax, if unavoidably melted to a greater or lesser extent, from running out through the hole 9.

A casting 16, entirely separate from the casting 5, is provided with a ledge 17 and with an upwardly extending supporting flange 18 and with ribs 19, these parts being integral. By means of screws 20 which extend through the ledge 17, the casting 16 is detachably held in position upon the pan-like member 5. The casting 16 is further provided with burner nipples 21, serving the purpose of gas burners of small size.

The general contour of the casting 5 and that of the casting 6 together with the upwardly projecting flange 18 is more or less analogous to the general contour of a sad iron, so that when a sad iron is rested upon the flange 18 it will neatly cover this flange and the parts immediately below it.

The casting 5 is provided with an annular lug 22 integral with it, and extending through this annular lug is a pipe 23, provided with a hand valve 24 and with a throat 25. The pipe 23 is further provided with air holes 26 located in immediate proximity to the throat 25. The pipe 23 is for supplying the gas, admixed with a suitable quantity of air into the casting 5, the gas then passing upwardly through the burner nipples 21.

The hand valve 24 may be adjusted at the will of the operator in order to control the flow of gas. The throat 25 and holes 26 are used in the conventional manner for securing the proper proportion of air in the gas used.

The device is quite economical in the use of gas, owing to the fact that the gas nipples 21 are so arranged as to distribute the burning gas uniformly against the under face of 5 the sad iron.

Between the upwardly extending flanges 18 are spaces 18^a, through which the burnt gases, vapors and flames can escape.

My device can be used for toasting bread 10 or cheese, or even for broiling meats or cooking certain small articles of food. It can also be used for heating a ladle or the like, and for very simple metallurgical operations, such for instance as roasting a small 15 specimen of ore.

The form of the casting 4 renders the casting specially adaptable for the purpose of being secured upon a board, a table, or even the trunk of a tree, by means of a strap 20 or a cord for the purpose.

The operation of my device may be readily understood from the foregoing description.

The parts being formed and assembled as 25 shown, and the pipe 23 being connected with a supply of illuminating gas or other combustible gas suitable for the purpose, the gas is turned on, and the gas rises upwardly through the burner nipples 21. 30 This gas being ignited, flames are produced in the manner known in this art. It generally suffices to light one or two of the jets, and from these the others are lighted automatically. In practice, a match is applied 35 almost anywhere over the top of the member 16 while the gas is passing upwardly through the burner nipples 21, the result being that the lighting of all of the gas jets is virtually simultaneously.

40 When the device is used for ironing, the sad iron is rested upon the flange portions 18 as above described, and heated by the gas flames. The sad iron is generally moved by hand, and its under face is cleaned and 45 partially polished by rubbing it over the cleaning pad 12. The iron is occasionally upon the top of the wax cake 14, so as to take a little wax upon its face, in the manner well understood in this art.

50 By the use of my device, owing to the convenience in the arrangement of the parts, a considerable saving of time can be effected.

I do not limit myself to the precise mechanism shown, as variations may be made 55 therein without departing from my inven-

tion, which is commensurate with my claims.

Having thus described my invention, what I claim as new and desire to secure by 60 Letters Patent is as follows:

1. A device of the character described comprising a pair of castings detachably connected together and each having a contour analogous to that of a sad iron, one 65 of said castings being provided with upwardly extending flanges and with ribs, said ribs and flanges being integral with said last mentioned casting, and means for admitting combustible gas in between said 70 castings.

2. A device of the character described comprising means for supporting and heating a sad iron, and a plurality of pan-like members integral with each other, and disks 75 of asbestos located within said pan-like members.

3. A device of the character described comprising a hollow casting having the general proximate form of a sad iron, a 80 casting provided with a number of pan-like members integral with each other, said second-mentioned casting being detachably mounted upon first-mentioned casting and having a general contour analogous to that 85 of a sad iron, said second-mentioned casting being provided with a plurality of burner nipples extending from said pan-like members, said second-mentioned casting being further provided with upwardly extending 90 flanges for supporting a sad iron.

4. A device of the character described comprising a pair of castings detachably connected together and having when thus connected a general contour analogous to 95 that of a sad iron, one of said castings being provided with a number of upwardly extending flanges for supporting a sad iron, and being further provided with a number 100 of upwardly extending ribs and with burner nipples interspersed between said ribs.

5. A device of the character described comprising a pair of castings detachably connected together so as to form when thus connected a hollow member having general 105 contour analogous to that of a sad iron, one of said castings being provided with upwardly extending flanges for supporting a sad iron and further provided with a number 110 of burner nipples located intermediate said upwardly extending flanges.

OTTO H. FRANK.
